US00D804133S

(12) **United States Design Patent** (10) **Patent No.:** **US D804,133 S**
(45) **Date of Patent:** **** Nov. 28, 2017**

(54) **TRASH CAN**

(71) Applicant: **simplehuman, LLC**, Torrance, CA
(US)

(72) Inventors: **Frank Yang**, Rancho Palos Verdes, CA
(US); **Di-Fong Chang**, Torrance, CA
(US); **Myk Wayne Lum**, Irvine, CA
(US); **Adam C. Wade**, Rancho Santa
Margarita, CA (US); **Tzu-Hao Wei**,
Hacienda Heights, CA (US)

(73) Assignee: **simplehuman, LLC**, Torrance, CA
(US)

(**) Term: **15 Years**

(21) Appl. No.: **29/548,018**

(22) Filed: **Dec. 9, 2015**

(51) LOC (10) Cl. **09-09**

(52) U.S. Cl.

USPC **D34/9**

(58) **Field of Classification Search**

(57) **CLAIM**

The ornamental design for a trash can, as shown and described.

DESCRIPTION

FIG. 1 is a top, front, left-side perspective view of a trash can showing our new design;

FIG. 2 is a top, rear, left-side perspective view thereof;

FIG. 3 is a front elevation view thereof;

FIG. 4 is a rear elevation view thereof;

FIG. 5 is a right-side elevation view thereof;

FIG. 6 is a left-side elevation view thereof;

FIG. 7 is a top plan view thereof; and,

FIG. 8 is a bottom plan view thereof.

The broken lines shown in the figures are for the purposes of illustrating portions of the trash can and form no part of the claimed design.

1 Claim, 7 Drawing Sheets
